(57) **CLAIM**

The ornamental design for an electronic security apparatus with tether, as shown and described.

DESCRIPTION

FIG. 1 is a top view of my new design for an electronic security apparatus with tether.

FIG. 2 is a bottom view of my new design for an electronic security apparatus with tether.

FIG. 3 is a front side view of my new design for an electronic security apparatus with tether.

FIG. 4 is a back side view of my new design for an electronic security apparatus with tether.

FIG. 5 is a left side view of my new design for an electronic security apparatus with tether.

FIG. 6 is a right side view of my new design for an electronic security apparatus with tether.

FIG. 7 is a top perspective view of my new design for an electronic security apparatus with tether partially installed.

FIG. 8 is a top perspective view of my new design for an electronic security apparatus with tether after installment; and,

FIG. 9 is a second top perspective view of my new design for an electronic security apparatus with tether after installment. The broken line showing of an electronic security apparatus and the box shown in FIGS. 7-9 represent unclaimed subject matter and form no part of the claimed design.
